UNITED STATES PATENT OFFICE.

WARREN P. JENNINGS, OF BROOKLYN, NEW YORK.

DESIGN FOR A LADY'S MITT.

SPECIFICATION forming part of Design No. 14,672, dated February 12, 1884.

Application filed December 19, 1883. Term of patent 7 years.

To all whom it may concern:

Be it known that I, WARREN P. JENNINGS, a resident of Brooklyn, in the county of Kings and State of New York, have invented and 5 produced a new and original Design for Ladies' Mitts, of which the following is a full description, in connection with the accompanying photograph, which represents a face view of my new design for a mitt.

10 This invention relates to a new design for ladies' mitts; and it consists in the arrangement of apertures that form figures for ornamenting the mitt, as hereinafter more fully described.

15 *a b* are rows of dots, between which are rows *d e* of figures, each of said figures being composed of several rows of dots, as shown, the figures *d d* alternating with the figures *e e*, as shown.

20 *f g* are rows of dots, having between them three rows, *h i j*, each of said rows *h i j* consisting of alternating series of dots and blank spaces, as shown.

k l are rows of dots having between them closely set rows *m n o* of dots.

25

I claim—

1. The design for mitts, the same consisting of the figures *a b d e*, substantially as shown.
2. The design for mitts, the same consisting of the figures *f g h i j*, substantially as shown.
3. The design for mitts, the same consisting of the figures *k l m n o*, substantially as shown.
4. The design for mitts, the same consisting of the figures *a b d e f g h i j*, substantially as shown.
5. The design for mitts, the same consisting of the figures *f g h i j k l m n o*, substantially as shown.
6. The design for mitts, the same consisting of the figures *a b d e f g h i j k l m n o*, substantially as shown.
